BOTTLE BREAKING DEVICE

William L. M. Legg, Brooklyn, N. Y.

Application May 11, 1936, Serial No. 79,141

1 Claim. (Cl. 83—93)

The present invention relates to an apparatus designed for the breaking of bottles and more particularly whiskey bottles.

In order to prevent the refilling of bottles containing an alcoholic beverage such as whiskey, there is in some localities a requirement that all such bottles be destroyed when empty. In order to comply with this requirement the bottle should be broken and by doing so in the usual manner presents a hazard due to the scattering of broken glass.

It is therefore the primary object of the invention to provide an apparatus which will efficiently and effectively destroy a bottle by breaking, which by its construction will overcome the hazard of scattering broken glass.

A still further object of the invention is the provision of a cabinet-like structure adapted to receive a bottle and disposed within said cabinet is weighted means which is manually controlled and adapted to contact a bottle supported within the cabinet to break the same.

The invention will be fully and comprehensively understood from a consideration of the following detailed description when read in connection with the accompanying drawing which forms part of the application.

In the drawing:

Fig. 1 is a perspective view of the new and improved apparatus; and

Fig. 2 is a longitudinal sectional view thru the apparatus.

Referring to the drawing for a more detailed description thereof, the cabinet structure is indicated generally by the numeral 5 and is substantially rectangular shaped. Access to the interior of the cabinet is obtained thru a door opening closed by a door 6 hinged to one end of the cabinet and for imparting visibility to the interior of said cabinet there is arranged a window 7 in one wall thereof. The cabinet may be constructed of any desired material and shape but the base thereof is preferably provided with a pad 8 of sponge rubber or the like which serves to withstand the shock of the depending weighted arm which contacts the bottle.

The bottle breaking means includes a cylindrical metallic casting 9 supported on and rising from the top surface of the cabinet 5, and the interior of said casting is hollow for slidably receiving a plunger rod 10 extending through the cabinet and which has threadedly secured to the inner end thereof a weighted element 11. The upper end of the rod has a knob 12 secured there-

to and which acts as a handle, as will be apparent.

The bore of the casting 9 is shaped to provide bearing means for guiding the rod, and the bore is enlarged below the bearing means to receive a coil spring 13 that surrounds the rod, and is engaged with the weighted member 11 to increase the action thereof when the rod is released from its latching means which will be presently described. It will be noted from Figure 2 that the mechanism is shown in raised or latched position, with the spring 13 under compression, in full lines and in bottle breaking position in dotted lines.

The latching means for the apparatus is in the form of a trigger mechanism which includes an arm 14 slidably mounted within a sleeve 15 formed on the casting 9 at right angles thereto, as shown, and the inner end of the arm 14 is tapered as at 16 to be received within an annular groove 17 in the rod 10. A spring 18 normally urges the arm 14 into engagement with the groove 17, and the spring 18 is held within the sleeve 15 by means of the cap 19 on the outer end of the sleeve. The arm 14 which serves as a trigger is actuated against the action of its spring, by means of a handle member 20 pivoted as at 21 to the casting 9 and its upper end is formed to provide a yoke, as best shown in Figure 1. A pin 22 bridges the yoke for movement in slots 23 of the sleeve 15 and extends transversely through the arm 14 for pivotal association therewith. By that construction, it will be apparent, that when the reduced portion 24 of the handle member 20 is engaged and pressure exerted inwardly, the pin 22 moves within the slot 23 to actuate the arm 14 so as to displace the same from the groove 17, whereupon the weighted member 11 will be forced downwardly by the action of gravity as well as by the spring 13.

Supported within the cabinet 5 is a removable tray 25 within which the bottle 26 to be broken is positioned for disposal in the path of the weighted member 11 and, as afore-indicated, access within the cabinet is obtained thru the door opening and said tray 25 may be removed for the positioning of the bottle 26 therein and also for the discharge of the broken particles of the bottle therefrom.

From the above description it is believed that the operation of the device is readily apparent. A bottle is first positioned within the tray 25 whereupon the member 20 is actuated to release the trigger arm 14 and the weighted member will then descend contacting the bottle 26 with sufficient force to break the same. The mechanism

is reset by grasping the handle portion 12 and pulling the same upwardly until the tapered end 16 of the trigger arm 14 is engaged within the groove 17, it being understood that the spring 18 normally urges said arm 14 toward the shaft 10.

It is to be understood that this improvement is capable of extended application and is not confined to the exact showing of the drawing nor to the precise construction described and, therefore, such changes and modifications may be made therein as do not affect the spirit of the invention nor exceed the scope thereof as expressed in the appended claim.

What is claimed as new is:

15. In a bottle breaking device, a display cabinet having a removable tray therein for receiving a bottle to be broken, and breaking means comprising a hollow cylindrical member mounted on said cabinet and rising therefrom, a plunger rod slidably mounted in said hollow cylindrical member and having an annular groove therein, said plunger rod having its lower end extending into the cabinet, a weighted member threadedly se-

cured on the lower end of said rod, a knob providing a handle on the upper end of said rod, a spring surrounding the rod and engaged with the weighted member for urging the latter to bottle breaking position, a slotted sleeve formed on said cylindrical member and extending at right angles therefrom, a trigger member slidably mounted in the sleeve and receivable in the groove for holding the weighted member in raised position, a handle member pivotally connected to the cylindrical member and including a yoke disposed about the slotted sleeve, a pin bridging the yoke and extending through the slots of the sleeve and the trigger member respectively for pivotal connection to the latter, a coil spring in the sleeve and engaged with the trigger member for normally holding the latter in the groove, and said trigger member handle being adapted for moving the trigger member against the action of its spring for releasing the rod to cause the weighted member to strike the bottle for breaking the latter.
